UNITED STATES PATENT OFFICE.

CLARENCE K. BALDWIN, OF CHICAGO, ILLINOIS, ASSIGNOR TO ROBINS CONVEYING BELT COMPANY, A CORPORATION OF NEW JERSEY.

COKE-WHARF.

1,287,179.

Specification of Letters Patent. Patented Dec. 10, 1918.

Application filed May 12, 1915. Serial No. 27,863.

To all whom it may concern:

Be it known that I, CLARENCE K. BALDWIN, a citizen of the United States, residing in Chicago, county of Cook, and State of Illinois, have invented a new and useful Improvement in Coke-Wharves, of which the following is a description.

This invention has reference to means for handling coke, and relates particularly to coke wharves and adjuncts thereto capable of handling and disposing of the coke according to the most approved and modern methods.

It should be understood that the coke is usually pushed from the ovens into a car with inclined bottom, said car having side doors hinged at the top so that they may be swung outwardly to enable the coke to slide out of the car into hoppers provided for its reception. The coke is usually quenched in the car by streams of water poured upon the surface of the mass. In the manufacture of coke it is a desideratum to apply just sufficient water to the mass to cool it, and then allow the coke to air-cool and drain so that it will not contain more than from three to four per cent. of moisture. The hoppers receiving the coke from the cars are arranged in a series approximately the length of the car, and in the hoppers the thickness of the bed of coke will vary from five to six feet, in the center, to from one to two feet at the upper edge. In the car, owing to the shape of the latter, the mass of coke is unequally quenched, that portion of the mass near the door of the car receiving the least water, while, at the top of the inclined portion, the mass receives the most water on account of the difference in the thickness of the mass. The unquenched portions of coke, when the mass is delivered from the car to the hoppers, is in the lower part of the latter, so that, in order to quench the same it becomes necessary to overquench the mass of coke surrounding the hot particles, it being, of course, understood to be impossible to quench the hot particles from the bottom. This necessary additional quenching in the hoppers has a tendency to increase the percentage of moisture in the mass of coke to much beyond the commercial limits. The coke in the hoppers, owing to the shape of the latter, will not cool evenly, since the mass is of different thicknesses or depths at different places in the hoppers.

With my construction, I have overcome the various objections noted in the foregoing, and, specifically, the following may be noted as among the important objects of my invention to provide means by which the mass of coke delivered from the quenching cars may be spread and exposed for cooling in an approximately uniform layer over a wharf specially provided and constructed for its reception, so that the mass will cool evenly by having a maximum area thereof exposed to the air; to so dispose the mass of coke, ejected from the cars, as to cause the hot particles of coke to become exposed, so as to enable them to be cooled without adding a surplus of water to particles already cooled; to provide simple and effective means for transferring coke from the wharf to a conveyer or vehicle disposed in proper coöperative relation to the wharf; to provide a means by which, as the mass of coke is delivered under control from the wharf, it may be evenly distributed on the conveyer or vehicle, so as to provide for uniform delivery of the mass to the screening mechanism; to provide means by which the operator may control the delivery of the mass to the conveyer or vehicle, so that, in case hot particles of coke present themselves to the controlling mechanism, the operator may immediately stop the flow of the mass and cool the said hot particles; and to provide a combination of simple, effective means which are inexpensive to produce, and arranged in manner such as to give the operator absolute control over the mass of coke delivered from the quenching cars and while it is in transit to the conveyer or vehicle, and by which means the several objects noted in the foregoing are effectively and commercially secured.

With the foregoing objects in view, and others which will be detailed during the course of this description, my invention consists in the parts, features and elements and combinations thereof hereinafter described and claimed.

In order that my invention may be clearly understood, I have provided drawings wherein:

Figure 1 is a vertical cross-section of a coke wharf embodying the features of my invention, some of the mechanisms thereof being shown in elevation; and

Fig. 2 is a front elevation of a section of

105

100

110

the coke wharf showing parts in section, and illustrating the controlling gates, rotary feeders, and a form of conveyer or vehicle arranged in coöperative relation.

5 It should be understood that the units constituting my invention may be arranged indefinitely, end to end, and in coöperative relation, so as to control the mass of coke and carry it away to the screens, according 10 to the location and size of the plant to be erected, and provided with the features embodying my invention. In the drawings I have illustrated three units comprising the controlling gates and rotary feeders arranged end to end, or in series, and in coöperative relation to a corresponding length or section of wharf and conveyer or vehicle.

15 Referring to the drawings, the numeral 1 indicates the trench or pit in which the conveyer, feeder and controller are disposed in coöperative relation and from which the wharf 2 is extended. The trench is preferably a cement or masonry construction, and is of such dimensions as to give ample 20 space for the various apparatus employed and for the operatives to work in. From one side of the trench the wharf 2 is extended upwardly at an inclination of approximately thirty degrees, although this inclination may be greater or less according to 25 conditions. The upper edge of the inclined wharf terminates at the vertical wall 3 beside which the railroad 4 is constructed, on which the quenching cars 5 travel. As 30 shown in Fig. 1, the cars have the inclined bottom 6 with swinging gates 7, the dotted line portion indicating the open position of the gates for discharging the coke upon the wharf.

35 40 The foundation of the wharf is, preferably, of cement or masonry, and the surface of the wharf has embedded therein rails or bars or I-beams, indicated at 8, these beams being of structural iron and having their top flange or head exposed above the surface of the wharf, so as to provide parallel rails or supports extending lengthwise of the wharf for supporting the metal-plates 9, which are arranged in overlapped relation 45 to the one to the other. The plates 9 are provided at their upper ends with depending flanges 10 adapted to hook over the heads of the beams 8 and thus be retained in position and prevented from sliding down 50 with the mass of coke; and by this structure being also rendered removable and replaceable at will. The upper plate 9 is held by its flange in coöperative relation with an angle iron or beam 11 permanently secured 55 to the upper edge of the wharf, as by bolts embedded in the structure of the wharf. The lower plates 9 are extended over the lower edge or face of the wharf, so as to overlap the top member 12 of a guard which 60 coöperates with the rotary-feeder and pre-

vents the coke from dropping into the pit 1 below the apparatus contained therein. This guard is composed of cast-iron, preferably, and, at its front wall 13, is made to conform to the curvature of the feeder, and, at its bottom, is secured by its flange 14 to one or more cross-beams 15 connected to uprights 16 suitably secured to the bottom of the pit, the cross-beams 15 being embedded in the walls of the pit, at their ends, so as to provide firm support therefor.

65 The beams 15 support journal bearings 17, see Fig. 2, for a shaft 18, which is any length desired and which extends lengthwise of the wharf within the pit and just below the lower end of the wharf. The shaft has mounted thereon, and fixed thereto, the series of rotary feeders 19 comprising hollow cylinders having longitudinal, parallel vanes or flanges 20 providing between them a series of pockets or receptacles 21 for the coke as it slides from the wharf onto the guard 12, under the control of the operator. The shaft 18 at one, or both, ends may be provided with a driving sprocket-wheel 22 driven by a chain from a motor, not shown, it being understood that, for the purposes of my invention, the sprocket-wheel 22 shall be considered the driving means for the rotary feeders. The adjacent ends of the feeders 19 are covered by the end guards 23 which, at one end, as shown in Fig. 1, coöperate with, and may be, securely attached to, the guard 12, and, at the other ends, coöperate with, and may be secured to, the supporting beams 15, these end guards having the function of protecting the bearings of the shaft 18 and preventing particles of coke, dust, grit, etc., from falling between the ends of the feeders, as will be readily understood. The end guards 23 are provided with brackets 24 affording bearings for the pivots 25 of controlling gates arranged, as shown in the drawings, end to end, or in series lengthwise of the wharf and in number corresponding to the feed-drums, a gate and drum constituting a unit in my invention which may be extended along the wharf indefinitely.

70 75 80 85 90 95 100 105 110 115 120 125 130 The controlling gates are formed preferably of the end frame members 26 connected together in pairs in triangular or substantially A-form, one of the members being, at each end of the gate, extended as indicated at 27 and having ears or bearings applied thereto in which a hand-rod 28 is securely set so as to be grasped by the operator to manipulate the gate. Another of the frame members, at each end of the gate, is extended as at 29 and the said extensions being weighted as at 30, the weight of which substantially counterbalances the weight of the gate overhanging the feeder, as shown in Fig. 1, thus rendering it easy for the operator to manipulate the gate. Another of

the frame members 26, at opposite ends of the gate, is extended as at 31, the two said extensions being connected by an angle iron 32, to which the upper ends of a series of 5 gate-bars or fingers 33 are rigidly, but removably, connected, the lower ends of said fingers being connected by the angle irons 34 at the inner end or angle of the gate structure. The lower ends of the gate-bars 10 or fingers 33 are preferably outwardly bent, as shown at 35, so as to rest upon the surface of the guard member 12 and form therewith an acute angle. The gate-bars or fingers 33 are arranged as closely together as desired 15 and in parallelism on the gate-frame, the arrangement, however, being such as to prevent the particles of coke or other material from passing between adjacent bars. Normally, the gate will rest, as shown in Fig. 1, 20 with the lower ends 35 of its bars or fingers in engagement with the guard 12, and the mass of coke sliding down the inclined wharf will, of course, have a tendency to maintain this normal position of the gates. 25 The counterbalancing weights 30, however, will render it easy for the operator, with very little downward pressure or pull at 28, to open the individual gates to any extent desired and as quickly as may be needed. 30 The operator, to manipulate the gates, walks along the platform 36, which may be composed of any suitable material and supported by the cross-beams 15, the wall of the pit, at one side, protecting the operator, and the rail or fence 37 at the other side preventing the operator from accidentally falling into the pit where the machinery is located, the said rail or fence being composed of uprights 16 and top bar or rail 38 connecting the same. 40 The coke sliding down the wharf 2, and received by the feeder 19, under control of the gate 26, is deposited upon a conveyer or vehicle of any form desired, the one adopted by me being preferable because of 45 its simplicity and capacity. This conveyer consists of an endless belt, the upper run 39 of which is supported on, and troughed by, the well-known Robins five-pulley troughing idlers 40, the supporting brackets of 50 which are bolted to the cross-beams 41 on the longitudinal beams 41^a which are supported in any suitable manner by the uprights 16. The lower run 42 of the conveyer-belt travels over idlers 43, journaled 55 in the brackets 44 on the longitudinal beams. This belt-conveyer, at its ends or "centers", encircles driving drums of usual construction, which are well-known and unnecessary to be shown in the drawings; but, it 60 should be understood that, in the claims, where the conveyer is mentioned, and unless otherwise specified, positive means are intended to be included for actuating the conveyer, regardless of the means or the char-acter of the conveyer. Preferably, the trend of this conveyer is parallel to the length of the wharf and the series of units, this arrangement necessarily economizing space and producing compactness of structure. It 70 is to be understood, however, that, in the claims where a conveyer is referred to, and unless otherwise specified, any form of movable vehicle adapted to coöperate with the feeders in the relation and positions indicated is intended to be included and comprehended by my invention.

From the foregoing, the mode of operation of my coke wharf will be readily understood in connection with the following: 80 The coke, usually quenched primarily in the car 5, is conveyed to the wharf, and, when the cars are in proper position for discharge the gates 7 thereof are swung open (see dotted lines, Fig. 1) thus discharging the contents 85 from the inclined bottoms 6 of the cars onto the plates 9 of the inclined wharf 2. The coke will slide down the wharf into engagement with the gate-bars or fingers, and, in so doing, will automatically become more or less evenly distributed. The hottest particles of the mass contained in the cars being at the bottom, will necessarily be first discharged upon the wharf and exposed to the cooling effects of the air and will slide down 95 into engagement with the gate-bars. In this position the hot particles are exposed and may readily be quenched with a small hose through the gate-bars. The rest of the mass may also be sprinkled, if desired, and 100 the water will naturally drain off down the inclined surface of the wharf, thus, by gravity, removing the greater percentage of moisture. The conveyer and the feeder being in operation, the gate, under control of 105 the operator, will be raised to the desired extent and the coke permitted to slide down the guard-member 12 into a receptacle 21 of the rotary-feeder, the filling of this feeder 110 being obviously under control of the operator, so that over-feeding and spilling are prevented. By the rotation of the feeder in the direction of the arrow *a*, Fig. 1, the speed of the said feeder and the speed of 115 the conveyer being proportioned, as required, the coke deposited in the receptacles 21 will be deposited lightly, and in measured quantity, and with little or no drop or fall onto the upper run 39 of the conveyer; and, as the coke is deposited in 120 measured quantities, according to the size of the receptacles, it is deposited in a uniform and continuous layer upon the conveyer and carried away, as required. As one unit section of the wharf is cleared of coke, the 125 gate is returned to normal position and the operator walks along to the next unit, opens the gate and clears the wharf at this section or unit, this being continued and the operations repeated until the entire length of the 130

wharf is cleared of coke. If the feeding is progressing too rapidly, control thereof is had by manipulation of the gates and thereby the deposit of coke in the receptacles of the feeders is controlled, as is also the amount passing to the conveyers. This is extremely important, since, if the coke is conveyed to the screens uniformly and continuously, the best results can be obtained.

10 Otherwise, non-uniform screening is liable to result, thus mixing the different classes and sizes of coke. It may be that the speed of the rotary feeders at any given time may be such as to give a greater throw to particles of the coke than is necessary to deposit the same in substantially the center of the conveyer 39, or the quantity deposited at any time may be such as to cause the top particles of the mass to roll toward the edges of the conveyer. To prevent such particles from rolling off the conveyer at either edge thereof, I have provided inclined guards 45 extending along one edge of the conveyer between, and supported by, the beams 15 and at the opposite side of the conveyer, under the rotary feeder, another series of guards 46, similar in character and inclination. These guards will prevent projected or rolling particles from overflowing the edges of the conveyer, and, also, will permit them to return to, or stay in proper position on, the mass deposited upon said conveyer.

In the drawings I have shown the conveyer, feeder-drum, controlling gates, and other coöperating parts disposed in a trench or pit 1, and I have found that this disposition and construction are very satisfactory; but, I desire it understood that the entire wharf structure may be built upon the "flat", or hills and embankments may be taken advantage of, as will be readily understood. This has reference to engineering skill and economy of disposition and in no manner imposes a limitation upon my invention.

For the purpose of this specification, I have described the treatment of coke; but, I desire it distinctly understood that my invention is not limited to coke treatment, but is adapted for the treatment or manipulation, discharge and conveyance of any other kind of granular materials, such as coal, ore, quartz, crushed stone, etc. However, the features of my invention are particularly adapted to frangible or friable materials or substances, since, by controlling the feed of the material, as by the "pocket feeder", and controlling the discharge of the material from the wharf to the feeder and the manner in which the feeder deposits the material upon the conveyer, such material is prevented from being ground, or crushed, or unduly broken by contact of its particles during manipulation. The form 65 of the feeder, moreover, contributes, in great

measure, to this result as well as the co-operative relation of the conveyer and the feeder, since, by providing a rotary pocket feeder, arranged as shown and described, and employing a troughed conveyer, the co-operative relation of the two can be made more or less intimate, thus reducing to the minimum the drop from one to the other. These are all important features of my invention, and upon them I desire to lay great 75 stress.

Having thus described my invention, what I claim and desire to secure by Letters Patent is:

1. A wharf having an inclined bed, in combination with a conveyer arranged below and extending longitudinally of the lower end of the bed, means for transferring material in measured quantities from the bed to the conveyer, and means for controlling the delivery of the material to the transferring means, said controlling means being arranged in proximity to the transferring means and comprising an upstanding skeleton frame structure pivotally supported at 80 its lower end outwardly beyond and having a portion overhanging the lower end of the bed, and a series of upstanding gate fingers rigidly supported by said overhanging portion to provide a vertically-movable barrier 85 between the bed and the transferring means.

2. A wharf having an inclined bed, in combination with a conveyer arranged below and extending longitudinally of the lower end of the bed, means for transferring material in measured quantities from the bed to the conveyer, and means for controlling the delivery of the material to the transferring means, said controlling means being arranged in proximity to the transferring means and comprising an upstanding skeleton frame structure pivotally supported at 90 its lower end outwardly beyond and having a portion overhanging the lower end of the bed, and a series of upstanding gate fingers rigidly supported by said overhanging portion to provide a vertically-movable barrier 95 between the bed and the transferring means.

100

105

110

115

3. A wharf having an inclined bed, in combination with a conveyer arranged below and extending longitudinally of the lower end of the bed, means for transferring material in measured quantities from the bed to the conveyer, and means for controlling the delivery of the material to the transferring means, said controlling means being arranged in proximity to the transferring means and comprising a pair of spaced triangular frame members having their outer basal portions pivotally supported beyond the lower end of the bed and their inner basal portions extending between the transferring means and the bed; parallel bars con- 120

125

necting the two frame members, and a series of upstanding gate fingers rigidly supported by said bars to provide a vertically-movable barrier between the bed and the transferring means.

4. A wharf having an inclined bed, in combination with a conveyer arranged below and extending longitudinally of the lower end of the bed, a rotary feeding drum journaled at the bottom of said bed and extending longitudinally thereof, said drum being provided with a plurality of circumferentially arranged pockets extending lengthwise thereof, means for rotating said drum, stationary guards at the ends of the drum, and means for controlling the delivery of the material from said bed to the drum, said controlling means comprising an upstanding skeleton frame pivotally supported at its lower end on the said guards and having a portion overhanging the bed, and a series of upstanding gate-fingers rigidly supported by said frame to provide a vertically-movable barrier between the bed and the transferring means.

5. A wharf having an inclined bed, in combination with a conveyer arranged below and extending longitudinally of the lower end of the bed, a series of rotary feeding elements arranged in end to end relation to each other at the bottom of said bed and extending throughout the length thereof, said elements being each provided with a plurality of circumferentially arranged pockets, means for rotating said elements, stationary guards at the ends of said elements, a series of independently movable gates arranged end to end lengthwise of the wharf at the lower end thereof and corresponding in number to the feeding elements, each of said gates including a frame pivotally supported on the adjacent guards and having a portion overhanging the lower end of the bed, and a series of up-standing gate fingers rigidly supported by said overhanging portion to provide a vertically movable barrier between the bed and the adjacent feeding element.

CLARENCE K. BALDWIN.
